COMPOSITION WOOD PANEL

William J. Runckel, Hood River, Oreg.

Application December 23, 1957, Serial No. 48,998

Term of patent 14 years

(Cl. D13—1)

Fig. 1 is a top plan view of a composition wood panel showing my new design;

Fig. 2 is an enlarged end view thereof looking in the direction of the arrows 2—2 in Fig. 1, with the center broken away for convenience of illustration;

Fig. 3 is an enlarged side view thereof looking in the direction of the arrows 3—3 in Fig. 1, with the center broken away for convenience of illustration; and

Fig. 4 is an enlarged fragmentary perspective view of the upper right corner of the panel shown in Fig. 1.

I claim:

The ornamental design for a composition wood panel, substantially as shown.
